DESIGN FOR A BROILER UTENSIL

John L. Bennett, Decatur, Ill., assignor to U. S.
Manufacturing Corporation, Decatur, Ill.

Application February 21, 1934, Serial No. 50,815

Term of patent 14 years

To all whom it may concern:

Be it known that I, John L. Bennett, a citizen of the United States, and a resident of Decatur, county of Macon, and State of Illinois, have invented a new, original, and ornamental Design for a Broiler Utensil, of which the following is a specification, reference being had to the accompanying drawing, forming part thereof.

In the drawing—

Figure 1 is a plan view of the article, showing my new design, the handle portion being broken away at an intermediate point.

I claim:

The ornamental design for a broiler utensil as shown and described.

JOHN L. BENNETT.
